FIG. 1.

FIG. 2.

INVENTOR
WILLIAM MALONEY.

BY *William Maloney*
F.M.G.

Patented Oct. 10, 1922.

1,431,536

UNITED STATES PATENT OFFICE.

WILLIAM MALONEY, OF OTTAWA, ONTARIO, CANADA.

LIGHT RAILWAY.

Application filed January 21, 1922. Serial No. 530,844.

To all whom it may concern:

Be it known that I, WILLIAM MALONEY, a subject of the King of Great Britain, and resident of the city of Ottawa, in the Province of Ontario and Dominion of Canada, have invented certain new and useful Improvements in Light Railways, of which the following is a specification.

This invention relates to improvements in light railways, such as may be used for suburban traffic, or around manufacturing or mining establishments, or for the conveying of material for roads, or for a great variety of other purposes all well known in the art.

15 The general objects of the invention are to provide a railway that may be constructed at low cost and yet will be possible of maximum capacity for passenger or freight traffic.

20 Further objects are generally to improve and simplify the construction of the railway to better adapt the various parts to perform the functions required of them.

And the invention consists essentially of 25 the improved construction hereinafter described in detail in the accompanying specification and drawings.

In the drawings:

30 Figure 1 is a transverse section of an elevation of an embodiment of the invention.

Figure 2 is a side elevation.

In the drawings, like characters of reference indicate corresponding parts in all the figures.

35 The railway is of the mono-rail type, comprising an upper supporting trough-spaced rail and a lower lateral bearing rail or member. In the embodiment illustrated I have shown double track construction but 40 the same principles may be applied to single track construction.

Referring to the drawings:

A, A represent the supporting rails, each comprising a lower semi-circular trough-shaped portion 10 and a flat side connection portion 11 extending upwardly beyond the outer edge of the trough-shaped portion 10 and being secured by suitable bolts to the posts B. These posts may be supported in 50 any convenient way, but preferably in the way illustrated, in which their ends are sunk into base blocks C of concrete or the like, being connected at the top by a cross-connecting brace 12 and at the bottom by a bracket 13 of U-shape, the sides of which are connected by suitable bolts with the

posts. The lower part of the posts B carry the lateral bearing members or tracks D.

E represents a car which may be designed for freight or passengers, and may be propelled by any suitable means such as a gasoline motor, or may be electrically driven, or drawn by a steam locomotive. The upper part of one side of the car is provided with stub-shafts 14 carrying wheels 15 fitting to and designed to run in the tracks. These wheels extend in a vertical plane. The bottom of the car is formed with lateral bearing wheels 16 turning in a horizontal plane and engaging the lateral bearing member D, the axis of these members being nearly in line with the side of the car, and the wheels themselves being supported on shafts 17 supported by Z-shaped brackets 18 which are braced with diagonal braces 19.

Additional support is given to the track A by means of diagonally extending tension rods 20, extending from U-shaped channel brackets 21 on the top of each post B, each 80 rod having spreaded ends extending through the flanges of the channel brackets with adjusting nuts thereon, the outer ends of the rods being connected to the track A. The lower tracks D may be connected at suitable 85 intervals with cross-braces 22.

It will be seen that the railway being composed of few parts, it may readily be assembled at low cost and with considerable speed.

90 As many changes could be made in the above construction and many apparently widely different embodiments of my invention within the scope of the claims, constructed without departing from the spirit 95 or scope thereof, it is intended that all matter contained in the accompanying specification and drawings shall be interpreted as illustrated and not in a limiting sense.

What I claim as my invention is:

1. A light railway comprising, in combination, a plurality of fixed posts, an upper track supported on the posts having a side portion connected to the posts and a trough-shaped portion designed to support the 105 wheels of a car, a lower lateral bearing member extending parallel with the track and supported from the posts, and channel brackets on the posts with tension rods extending from the flanges of the channel 110 brackets to the track between the posts.
2. A double light railway comprising pairs

of spaced posts, the posts of each pair being connected by trough braces and having a base block into which the posts extend, connecting brackets on the base block connected 5 to each post, tracks supported on the upper part of the posts, each comprising a trough-shaped portion and a side portion connected to the tracks, and bearing members extend-

ing parallel to the track mounted on the lower parts of the posts.

In witness whereof I have hereunto set my hand in the presence of a witness.

WILLIAM MALONEY.

Witness:

RUSSEL S. SMART.
